CLAIM

The ornamental design for a lens and frame for warning lights, as shown and described.

DESCRIPTION

FIG. 1 is a perspective view of a lens and frame for warning lights showing our new design;

FIG. 2 is a top plan view thereof;

FIG. 3 is a right side view, the left side being a mirror image thereof;

FIG. 4 is a bottom plan view thereof;

FIG. 5 is end view, the opposite end being identical thereof;

FIG. 6 is a perspective view of a second embodiment of our design;

FIG. 7 is top plan view thereof;

FIG. 8 is right side view, the left side being a mirror image thereof;

FIG. 9 is a bottom plan view thereof; and,

FIG. 10 is an end view, the opposite end being identical thereof.
